YARN SMOOTHING APPARATUS AND
METHOD

Allison Allen Wood, Lanett, Ala.

Application April 15, 1946, Serial No. 662,238

4 Claims. (Cl. 28—28)

1

The instant invention relates to the application of size to warp yarns and is more particularly concerned with novel means for obviating the formation of outwardly projecting fibers on the size-treated strands.

Heretofore, in the sizing of yarns, it has been customary to feed a plurality of continuously moving strands of yarn from a source of supply, such as a section beam, to a size box containing the sizing composition. After passing through the sizing composition, the moving strands, which may comprise as many as 2400 filaments or ends, are fed to the slasher provided with a plurality of drier rolls or cylinders. The sized strands as they move to the drier rolls are separated and apportioned to the individual rolls. Thus, assuming that 2400 unit strands or ends leave the size box and that the slasher has six drying cylinders or rolls, four hundred strands would pass over each roll. After leaving the drier rolls the moving dried sized strands are delivered by guide rolls to a single outlet. The serious objection to this prior practice has been that when the dried strands are separated, small fibers are found to be projecting outwardly from the respective strands. The instant invention is directed to the elimination of this objectionable feature by means of a plurality of rolls having a series of laterally spaced grooves in a manner to be described more in detail hereinafter, and illustrated in the appended drawings to which reference is now made, and in which—

Fig. 1 is a diagrammatic side elevational view of the size box, the slasher frame and its drier rolls;

Fig. 2 is an elevational view of a portion of a roller having a series of laterally spaced circumferential grooves hereinafter designated as a "buster" roll;

Fig. 3 is a sectional view on an enlarged scale showing the sized strands being separated and passing over pairs of "buster" rolls;

Fig. 4 is a sectional view through a sized strand prior to passage over a "buster" roll;

Fig. 5 is a view similar to Fig. 4, showing a sized strand after passage over the first of a pair of "buster" rolls; and

Fig. 6 is a view similar to Figs. 4 and 5 showing the sized strand after passage over the pair of "buster" rolls.

Referring first to Fig. 1, the reference character B designates the size box through which passes the continuously travelling mass or sheet of individual strands of yarn 10 from a plurality of section beams (not shown). The mass of

2

strands pass over a rotating idler roll 11 positioned above the cover 12 of the size box B, and then through an opening 13 in the cover 12. Size box B, as shown, is what is known as the V-type and is characterized by having a bird cage immersion roll 14 therewithin at the apex of the V below size level 14a, said immersion roll also being an idler. A pair of horizontally spaced similar driven copper rolls 15 and 16 are positioned within the size box B above size level 14a, each copper roll having a heavy fabric-covered squeeze roll 17 and 18, respectively, cooperating therewith. It will now be seen that the mass of strands 10 move from the section beams over rotating idler roll 11 through opening 13 in the cover 12 of the size box B, into the size composition, over the bird cage immersion roll 14, then out of the size and between driven copper rolls 15 and 16 and their cooperating squeeze rolls 17 and 18, then over an idler roll 19, and through opening 13 in the size box and over another idler roll 19a.

The mass or sheet of sized strands 10 now move over a pair of cooperating directional rollers 20, 20a, at which point the strands are equally divided into two masses 10a and 10b, mass 10a passing over roller 21 and mass 10b over roller 22. Each mass of strands 10a or 10b, as it leaves rollers 21 or 22, respectively, is separated into individual strands to pass over a pair of similar spaced "buster" rollers 23, 24. By reference to Fig. 4, it will be seen that there are twelve pairs of such rollers and by reference to Fig. 2, it will be noted that each roller has a series of laterally spaced circumferential grooves 25, with each groove receiving a single strand of yarn, so that the total number of grooves in all the twelve pairs or twenty-four "buster" rolls is equal to twice the total number of strands of yarn. It will also be seen that each pair of "buster" rolls 23, 24 is arranged in different horizontal planes so that each yarn strand takes a horizontally staggered path as it passes between the "buster" rolls. The latter are driven in the direction of the travel of the yarn strands at a much higher speed than the strands move. Each strand has free fibers pointing in the direction of travel of the yarn and as each strand passes over a pair of "buster" rolls, both the top and bottom halves of the strand is smoothed, one roll smoothing the bottom half and the other roll the top half of the strand. The grooves inhibit rolling or crawling of the strands. Fig. 4 shows a strand of yarn in section prior to passing over a "buster" roll; Fig. 5; after the lower half has been smoothed

by a "buster" roll, and Fig. 6, after both halves have been so treated.

From the pairs of "buster" rolls 23, 24, the individual strands of the continuously moving yarn passes to a plurality of spaced drying cylinders or rolls 26, which are also circumferentially grooved, with each drier groove receiving a strand from a corresponding groove in its "buster" rolls. The drying cylinders 26 are mounted for rotation in a slasher frame 27, twelve drying cylinders being shown. Assuming that 4800 strands of yarn leave the size box B, these will be divided into two batches of 2400 strands as they leave directional rollers 20, 20^a, and pass over rollers 21 and 22. Each mass 10^a and 10^b of 2400 strands is now divided into six batches of 400 strands each, so that each of the cooperating "buster" rolls has 400 grooves and each drying cylinder 26 also possesses 400 grooves. Each strand of yarn is accordingly now smooth and dry and rod-like with the fibers firmly smoothed down against the body of the strand. After leaving the driers 26 all the strands are reunited at 28 and fed to the slasher head and loom beam. When the strands treated as herein described are separated in the loom, it will be found that no loose fibers stick out or project from each strand.

From the above, it will be apparent that the objects of the invention have been attained. Various changes will be apparent to those skilled in the art, and it is contemplated to cover all such and to be limited in this respect only as may be necessary by the scope of the claims here-to appended.

What I claim and desire to secure by Letters Patent is:

1. Apparatus for sizing a sheet of yarn strands comprising a size box, means for continuously moving the sheet of strands through size in the box, means for separating the sheet of sized strands into equally divided masses, rolls for

separating the masses into strands and for smoothing each strand, and means for drying the smoothed strands.

2. The structure of claim 1, each of said rolls being circumferentially grooved.

3. The structure of claim 1, each of said rolls having a plurality of laterally spaced circumferential grooves.

4. Apparatus for sizing a sheet of yarn strands comprising a size-containing box having immersion and feed rolls, said strands continuously moving over said immersion and feed rolls, other rolls for separating said sheet of sized yarn into equally divided masses, a plurality of pairs of spaced "buster" rolls over which said masses are separated into sized strands, each "buster" roll having a plurality of laterally spaced circumferential grooves, the total number of grooves in all of said pairs of "buster" rolls being equal to the total number of yarn strands being sized, one groove of each pair of "buster" rolls smoothing the top half of a sized strand and a groove in the other of each pair of "buster" rolls smoothing the bottom half of the same strand, and a plurality of drying rolls drying the smoothed sized strands.
